UNITED STATES PATENT OFFICE.

LOUIS SCHWARTZ, OF NEW YORK, N. Y.

HANDLE FOR SAFETY-RAZORS.

991,377.

Specification of Letters Patent.

Patented May 2, 1911.

Application filed April 1, 1909. Serial No. 487,141.

To all whom it may concern:

Be it known that I, LOUIS SCHWARTZ, a citizen of the United States, and a resident of the city of New York, borough of Manhattan, in the county and State of New York, have invented a new and Improved Handle for Safety-Razors, of which the following is a full, clear, and exact description.

The invention relates to safety razors, and has for its object to provide a handle for safety razors, in which a blade can be quickly and effectively clamped.

A further object of the invention is to provide a handle, the parts of which can be readily taken apart or assembled.

A still further object of the invention is to construct the head member which holds the blade, in such a way that it can be removed without removing any other parts from the handle.

The invention consists in the construction and combination of parts to be more fully described hereinafter and particularly set forth in the claims.

Reference is to be had to the accompanying drawings forming a part of this specification, in which similar characters of reference indicate corresponding parts in all the figures.

Figure 1 is a longitudinal central section through a safety razor constructed according to my invention, certain parts being shown in elevation, this view being taken in a plane passing through the longitudinal axis of the blade; Fig. 2 is a longitudinal central section through the handle of the razor, certain parts being shown in elevation; the blade and the keeper are removed from the handle; and Fig. 3 is a view looking at the end of the razor which carries the blade, and representing how the blade is held on the guard.

Referring more particularly to the parts, and especially to Fig. 1, 1 represents a tubular handle, in which there is rotatably mounted a stem 2 having a threaded extremity 3, as shown. The rear end of this stem is provided with a substantially spherical shell 4, in the inner side of which an opening 5 is formed, which enables the shell to be received over the butt end of the handle. This opening seats against an annular rib or collar 6 which is formed on the handle, as shown. On the stem 2 an enlargement or collar 7 is formed, and the rear end or shoulder 8 of this collar lies near the

rear end of the stem. At the rib 6 a set screw 9 is inserted. This set screw projects into the interior of the handle and engages the shoulder 8 so as to prevent the stem from being removed without removing the screw. On the opposite end of the handle, as indicated most clearly in Fig. 2, a curved guard or comb 10 is provided, and this guard is provided with guard teeth or fingers 11 at its side edges, and these side edges are not parallel, but converge toward each other, as shown.

The blade 12 is of thin steel or similar material, and presents oppositely disposed cutting edges 13 which will converge as indicated in Fig. 3, so that the blade conforms in outline to the shape of the guard. The blade is clamped upon the outer face of the guard by means of a keeper 14, the body of which is in the form of a curved plate, the side edges 15 of which converge like the side edges 13. The width of this keeper is slightly less than the width of the blade so that the edges of the blade project, as indicated in Fig. 3. The keeper is formed with a shank 16 which extends into the hollow handle, and the inner extremity of this shank is formed with a threaded bore 17 which engages the threaded extremity 3 of the stem 2.

The side of the shell 4 is formed with a knurled zone or belt 18 which facilitates the rotation of the stem 2. When the stem is rotated in the proper direction, the keeper will be drawn toward the guard 10 so as to clamp the blade in position. The blade is provided with the usual opening 19, and the inner side of the keeper is provided with a spur 20 which passes through this opening and through a similar opening 21 which registers therewith and which is formed in the guard. This spur 20 holds the blade in position, and acts as a guide for the keeper when it is being drawn in by rotating the head or shell 4. It will be evident that by rotating the shell 4 in a proper direction, the keeper will travel outwardly so that it can be removed from the handle to enable the blade to be removed. Attention is called to the fact that this is accomplished without removing any other parts, so that for all intents and purposes the razor comprises simply two parts in addition to the cutting blade.

In shaving with the razor the narrow end of the blade is always held toward the front,

and, hence, one of the cutting edges will be applied to the right side of the face, and the other to the left side. Attention is also called to the fact that having the greatest width of the blade at the rear portion of the face is also advantageous, as in shaving at the ear and under the jaw, the outer portion of the blade at this point can be kept within the range of vision and in this way the blade can be used with greater dexterity and facility without cutting the projecting parts of the ear or jaw.

Having thus described my invention, I claim as new and desire to secure by Letters Patent,—

1. A safety razor, comprising a guard having a tubular handle projecting at right angles thereto, the handle being provided with an external rib adjacent to its outer end, a keeper plate provided with a shank projecting into the handle and having a threaded bore, a stem having its inner end screw threaded and screwing into the bore of the shank of the keeper plate and provided at its outer end with a spherical shell having an opening therein, said shell receiv-

ing the outer end of the handle and seating against said rib, and means for locking the stem in the handle.

2. A safety razor, comprising a guard 30 having a tubular handle projecting at right angles thereto, the outer end of the handle being provided with an external rib, a keeper plate provided with a shank projecting into the handle and having a 35 threaded bore, a stem having its inner end screw-threaded and screwing into the bore of the shank of the keeper plate, the stem being provided near its outer end with a collar and at said end with a shell having an 40 opening therein, said shell receiving the end of the handle and seating against the rib thereof, and a screw near the outer end of the handle and against which the collar of the stem abuts.

In testimony whereof I have signed my name to this specification in the presence of two subscribing witnesses.

LOUIS SCHWARTZ.
